UNITED STATES PATENT OFFICE.

ROBERT MCKNIGHT, OF SARNIA, ONTARIO, CANADA, AND JAMES W. BERRY, OF MARINE CITY, MICHIGAN.

COMBINED CLOCK AND ELECTRIC SWITCH.

1,289,502.

Specification of Letters Patent. Patented Dec. 31, 1918.

Application filed May 9, 1917. Serial No. 167,395.

To all whom it may concern:

Be it known that we, ROBERT MCKNIGHT, a British subject, residing at Sarnia, Lambton county, Ontario, Canada, and JAMES W. BERRY, a citizen of the United States, residing at Marine City, county of St. Clair, State of Michigan, have invented a certain new and useful Improvement in Combined Clock and Electric Switch, and declare the following to be a full, clear, and exact description of the same, such as will enable others skilled in the art to which it pertains to make and use the same, reference being had to the accompanying drawings, which form a part of this specification.

Our invention relates to a combined clock and electric switch for use on motor driven vehicles to automatically turn on the front and rear lights of the vehicle at a predetermined hour.

It is well known that the ordinances of many cities require that the signal lamps of all motor vehicles shall be lighted at a certain hour in the evening, but frequently the owner of a vehicle having parked his car earlier in the day neglects this requirement and thereby inadvertently makes himself liable to a fine.

One of the objects, therefore of this invention is to provide a device which is inexpensive in construction and effective in operation and which may be "set" to automatically turn on the signal lights of a vehicle at any required hour, or which may be manually operated to switch on or off the lights as required.

With the foregoing and other objects in view which will appear as the description proceeds, the invention resides in the combination and arrangement of parts and in the details of construction hereinafter described and claimed, it being understood that changes may be made in the precise embodiment herein disclosed without departing from the spirit of our invention.

In the accompanying drawings forming part of this specification:—

Figure 1, is a front elevation of the clock with a portion of the dial and frame broken away to show the switch beneath.

Fig. 2, is a cross sectional view through the device and indicating a fragment of the dial in elevation.

Fig. 3, is an elevation with parts broken away and in section as viewed from the side 55 opposite that shown in Fig. 2.

Fig. 4, is a detail sectional view of the switch taken on line 4—4 of Fig. 3.

Fig. 5, is a detail cross-sectional view through the friction disk and coöperating gears taken on line 5—5 of Fig. 3.

Referring now to the letters of reference placed upon the drawings:—

A, denotes the clock frame. B, indicates the clock dial. C, the hour hand, and D, the minute hand actuated by a clock mechanism E, of the usual form of construction;—it therefore requires no special description or detailed drawings as it forms no part of the invention.

F, indicates one member of a knife switch attached by a screw F', (forming one of the switch terminals) to the insulating plate G, secured to the clock frame. H, denotes a swinging switch arm pivoted to the bolt H', 75 projecting through the insulating plate G;—the bolt also serves as the other switch terminal. H², is a spring coiled around the bolt H', one end of which extends through a hole in the insulating plate, while the other bears 80 upon the swinging arm H, to force it into the switch member F, to close the circuit through the wires I, I', leading to a battery and electric lamps (not shown).

J, denotes a gear driven by the pinion E', 85 of the clock mechanism, so timed as to make a complete revolution every twenty-four hours. The gear J, is supported by a stub shaft J', projecting from the clock frame.

J², is a thimble sleeved upon the shaft J', on 90 which the gear J, is mounted. K, is a friction disk also mounted on the thimble J², lodged in a countersunk portion of the gear J, and carrying a stud K', the purpose of which will be hereafter explained. J³, is a 95 flange projecting from the thimble soldered to the disk K, and J⁴, is a washer spaced from the flange to receive between it and the flange the disk K, and gear J, that the latter may be held in frictional driving relation 100 with each other;—but while the disk is thus caused to rotate with the gear it may be manually adjusted with reference thereto by

the application of a key (not shown) to the squared end of the thimble J², when it is 105 desired to alter the relative operation of the

parts, or to operate the disk independently of the gear.

L, is an L-shaped swinging arm or member pivoted at L', to the clock frame, adapted to be tripped by the stud K', projecting from the disk K, upon the rotation of the latter. The L-shaped member L is pivoted intermediate of its ends to form a relatively short element and an L-shaped arm and the said short arm is arranged to coöperate with the operating portion of the movable member of the switch. The movable member of the switch is pivoted intermediate of its ends to provide the operating arm or portion and a switch arm to coact with the relatively fixed member of the switch. L², is a pin projecting from the end of the arm L, to receive the thrust of the push button M, supported in the wall of the clock frame. L³, is a spring bearing upon the end of the arm L, to return the latter to its initial position when tripped through the rotation of the stud K', carried by the disk K. L⁴, is a slot through which the end of the pin L², projects serving to limit the movement of the arm L.

M', is a push button adapted to bear against the stud H³, of the switch arm H. M², is a spring in each of the push button housings to return the push button to its initial position when released.

Having indicated the several parts by reference letters the construction and operation of the device will be readily understood.

For the purpose of this description it will be assumed that the clock has been "set" to switch on the lights (not shown) at about 4.55 and on reference to Fig. 1 of the drawings it will be noted that the stud K' carried by the disk K, which rotates in the direction indicated by the arrow, has released the L-shaped swinging arm carrying the pin L², controlling the release of the swinging switch arm H;—the spring H², of the latter being adapted to force the arm into contact with the other member F, of the switch, thereby closing the circuit through the battery and lamps (not shown) thus lighting the lamps, as will be readily understood. When it is desired to cut out the lights, or to again set the switch, the push button M', is operated to bear against the stud H³, forcing back the switch arm H, against the action of its controlling spring until engaged by the pin L², of the arm L, as shown in Fig. 2, thereby cutting out the lights and putting the device in condition to be again automatically operated on the following evening at the predetermined hour. If desired the lights may be switched on before the hour set for the automatic operation of the switch, by releasing the switch arm H, through the operation of the push button M:—its inner tapering end serving

to crowd over the pin L², carried by the arm L, thus releasing the switch arm H, held open by said pin against the action of the controlling spring H². To change the hour by which the switch may be automatically operated, the hour hand of the clock is turned in the usual manner to the hour it may be desired to switch on the lights:—the friction disk K, is then rotated by means of a suitable key inserted over the squared end of the thimble J³, until the stud K', (the position of the latter being indicated by the index mark K²) is in position to trip the arm L, as shown in Fig. 2, of the drawings.

The hour hand is then set to the time of the day and when through the operation of the clock mechanism it arrives at the predetermined hour for the release of the switch arm the latter will be actuated and the lights turned on in the manner before described.

Having thus described our invention what we claim is:—

1. A device of the class described, including two switch terminals electrically insulated from each other, a relatively fixed switch member mounted on one of the terminals, a movable switch member pivoted intermediate of its ends by the other terminal and coacting with the relatively fixed member to close the switch, a spring connected with the movable switch member for urging the same to its closed position, said movable switch member having an operating portion, a substantially L-shaped member pivoted intermediate of its ends and having an L-shaped arm and a relatively short arm provided with means for engaging the operating portion of the movable switch member for holding the switch open and a gear designed to be arranged in mesh with the train of gearing of a clock mechanism and provided with means for engaging the L-shaped arm of the said L-shaped member to move the same out of engagement with the operating portion of the switch to permit the spring to close the said switch.

2. A device of the class described including a casing, two switch terminals electrically insulated from each other, a relatively fixed switch member mounted on one of the terminals, a movable switch member pivoted by the other terminal and coacting with the said fixed member to close the switch, a spring connected with the movable switch member for urging the same to its closed position, a substantially L-shaped member pivoted intermediate of its ends and having a relatively short arm provided with means for engaging the movable switch member for holding the same in its open position against the action of the said spring, a gear designed to be arranged in mesh with the train of gearing of a clock mechanism and provided with means for engaging the L-

shaped arm of the said L-shaped member for releasing the movable switch member and spaced push buttons mounted on the casing, one of the push buttons being arranged to engage the movable switch member for opening the switch and moving the said switch member into engagement with the L-shaped member, and the other push button being arranged to engage the L-

shaped member to release the switch member manually.

In testimony whereof, we sign this specification in the presence of two witnesses.

ROBERT MCKNIGHT.
JAMES W. BERRY.
